By his Attorney,

F.W. Richards,

UNITED STATES PATENT OFFICE.

HUBERT K. WOOD, OF HARTFORD, CONNECTICUT.

DESIGN FOR A FOOD-CHOPPER FRAME.

SPECIFICATION forming part of Design No. 33,134, dated August 28, 1900.

Application filed July 2, 1900. Serial No. 22,382. Term of patent 7 years.

To all whom it may concern:

Be it known that I, HUBERT K. WOOD, a citizen of the United States, residing in Hartford, in the county of Hartford and State of Connecticut, have invented and produced a new and original Design for Food-Chopper Frames, of which the following is a specification, reference being had to the accompanying drawings, in which—

- 10 Figure 1 is a perspective view of a food-chopper frame, showing my new design. Fig. 2 is a side elevation of said frame; and Fig. 3 is a section taken on line α α , Fig. 2, looking downward.
- 15 As shown in the drawings, the leading or material features of my design consist of an outwardly-curved standard, (designated by the numeral 5,) said standard depending from the case or barrel 6 of the food-chopper frame 20 and being provided with concavities 7 7', Fig. 3, merging into a rounded rib 8 on the inner side, located at about the longitudinal axial line of the standard, and also into rounded edges 9 9' at the back, which give a graceful 25 appearance to the structure. At its lower end

the standard is provided with lateral projections or feet 10 10', having convex tops 10² and flat bottoms 10³, and the front of the standard has a depression 5², with curved walls merging into the projections 10 10' on 30 curved lines and also into the widened base 8' of the rib 8 between the seats 7 7' by easy curves. Below these feet or projections the standard is provided with a clamping portion having a straight inner wall 12 with a longitudinal rib 12' at the back, and projecting from this clamping portion is an arm 13, having the usual threaded seat.

Connected to the circular barrel 6 is the usual hopper 14, and this is of ovoid form and 40 joins the barrel by easy curves.

Having described my invention, what I claim as new, and desire to secure by Letters Patent, is—

The design for a food-chopper frame, substantially as shown and described.

HUBERT K. WOOD.
